United States Patent Office

Des. 214,461
Patented June 17, 1969

214,461

LANTERN

Reed P. Gardner, 1803 Bayview Ave.,
Belmont, Calif. 94002

Filed July 19, 1968, Ser. No. 12,828

Term of patent 14 years

Int. Cl. D26—03, 04

U.S. Cl. D48—31

FIG_1

FIG_3

FIG_2

FIG_4

FIG. 1 is a perspective view of the lantern embodying my new design;

FIG. 2 is a front elevational view of the lantern, the other sides being mirror images thereof;

FIG. 3 is a top plan view of the lantern; and

FIG. 4 is a bottom plan view of the lantern.

The support pole is shown in broken lines in FIGS. 1 and 4 for illustrative purposes only.

I claim:

The ornamental design for a lantern, as shown and described.
